UNITED STATES PATENT OFFICE.

JOSEPH UBERT DUBY, OF LONGBRANCH, NEW JERSEY, ASSIGNOR OF ONE-HALF TO WILLIAM N. SHINN, OF LAKEHURST, NEW JERSEY.

CARPENTER'S TOOL.

SPECIFICATION forming part of Letters Patent No. 700,023, dated May 18, 1902.

Application filed September 6, 1901. Serial No. 74,505. (No model.)

To all whom it may concern:

Be it known that I, JOSEPH UBERT DUBY, a citizen of the United States, residing at Longbranch, in the county of Monmouth and State of New Jersey, have invented certain new and useful Improvements in Carpenters' Tools, of which the following is a full and complete specification, such as will enable those skilled in the art to which it appertains to make and use the same.

The object of this invention is to provide and improve a combination-tool for carpenters of the class known as "squares," and which may be used as a try-square, pitch-cut square, hip-cut square, miter-square, and also for the purpose of drawing circles, gaging lumber, making octagonal cuts, and for many other purposes; and with these and other objects in view the invention consists of a combination-tool of the class specified constructed as hereinafter described and claimed.

In the drawings forming part of this specification, in which similar reference characters designate the same parts in each of the views, Figure 1 is a view of one side of my improved combination tool or square; Fig. 2, a view of the opposite side thereof; Fig. 3, a cross-section on the line 3-3 of Fig. 1; Fig. 4, a diagrammatic view showing the method of operating my improved tool in forming rafter-pitches and hip-cuts; Fig. 5, a view similar to Fig. 4 showing the method of operating my improved tool in gaging lumber; and Fig. 6, a view similar to Fig. 4 showing the method of operating my improved tool in drawing circles.

In the practice of my invention I provide a tool of the class specified which comprises an elongated base 7, into which is set a metal plate 8, and the base 7 is preferably composed of two parts, 7^a and 7^b, and one of said parts—that designated by the reference character 7^b—is one-eighth of an inch narrower than the other part.

The front edge of the base 7, into which the plate 8 is set, is a straight edge, and one end of said base is formed at a right angle to said edge, as shown at 9, and the other end is formed at an angle of forty-five degrees to said edge, as shown at 10, and the last-named

end constitutes the miter end of my improved square or tool.

The edge of the plate 8 opposite the back of the base 7 is cut out to form a right angle at 11, which point is opposite, or nearly opposite, the longitudinal center of the base 7, and by cutting out the said edge of the plate 8, as above described, the said plate is divided into two arms 8^a and 9^a, and the outer edge of the arm 8^a is in line with the straight end 9 of the base 7, and the outer edge of the arm 9^a of said plate is in line with the miter end 10 of the base 7.

The inner edge 12 of the arm 9^a of my improved tool is provided on one side with an ordinary scale 13, representing inches and parts thereof, and in direct line with the said edge of said arm 9^a and adjacent to the base 7 said plate 8 is provided with a hole 14, which is one inch from the angle 11 in the plate 8 7c and constitutes part of the scale 13.

The arm 8^a of my improved tool is provided on one side and at the outer edge thereof with a scale 15, which constitutes the hip-cut scale and the scale-marks of which are designated by the numerals "1" to "12," inclusive, and the spaces of which are irregular, as shown in Fig. 1, and said arm of the tool is provided on the opposite side and at the outer edge thereof with a scale 16, the scale-marks of which are designated by the scale-numerals "1" to "12," inclusive, and the spaces of which are irregular, as shown in Fig. 2, and the scale 16 is the rafter-pitch scale. The said arm 8^a of the tool is also provided with two rows of pencil-holes 17, arranged as shown in Figs. 1 and 2, and on the side adjacent to the wider part 7^a of the base 7 the outer row of these holes is provided with scale-numbers "1, 1, 1 $\frac{1}{2}$, 2," &c., and the other row is provided with scale-numbers "1 $\frac{1}{4}$, 1 $\frac{1}{4}$, 1 $\frac{1}{4}$, 1 $\frac{1}{4}$," &c.

On the side of the arm 8^a opposite that shown in Fig. 1 the holes 17 in the inner row are provided with scale-numbers "1 $\frac{1}{8}$, 1 $\frac{1}{8}$, 1 $\frac{1}{8}$, 1 $\frac{1}{8}$," &c., counting from the base 7, and the holes in the outer row are provided with scale-numbers "1 $\frac{1}{8}$, 1 $\frac{1}{8}$, 1 $\frac{1}{8}$, 1 $\frac{1}{8}$," &c., counting from the base 7.

The main object of providing the separate rows of holes 17 in the arm 8^a of the tool is to adapt the device for use in gaging timber, 100

and one method of using the device for this purpose is shown in Fig. 5, in which the reference-numeral 18 designates a piece of lumber, and if it be desired to gage this lumber into strips, as shown in the drawings, the narrower side ^{7b} of the base 7 of the tool is pressed against the edge of the lumber and a pencil-point passed through the holes 17 successively, beginning with the hole adjacent to the base 7, and the tool is moved along the surface of the lumber, and the lumber will be divided into quarter-inch strips, and the result will be the same if either side of the tool be used separately in this manner, except that when the wider side of the base 7 is pressed against the edge of the timber the first division will be only one-eighth of an inch wide. By using the tool as shown at the left of Fig. 5 and then reversing the tool and using the opposite side against the same edge of the timber the spaces on the timber will be one-eighth of an inch wide. The holes 17 may also be used for drawing circles, as indicated in Fig. 6, in which case the tool is placed on a piece of timber 19 and a bradawl or other device is passed through the hole 14, while a pencil-point is passed through one of the holes 17, and the tool may then be turned in either direction, so as to form a circle, and the diameter of the circle will depend upon the hole 17 through which the pencil-point is passed.

In Fig. 4 I have shown at 20 a method for determining a rafter-pitch or pitch-cut, and in this operation the base of the tool is pressed against the edge of the timber 21, the wider side of said base being down and the miter end of the tool being turned from the operator. In this operation the first line drawn at 22 will form an angle of forty-five degrees, and then by turning the end of the tool adjacent to the operator outwardly, as indicated in dotted lines, a pitch-angle at 16 of various degrees may be formed, as indicated at 24 and 25, the scale 16 serving to fix the number of inches to the foot in the pitch or pitch-cut of a rafter or rafters.

The method of operating the tool to determine a "hip-cut" is indicated at 26 in Fig. 4, and in this operation the position of the tool is reversed, the narrower edge of the base being pressed against the edge of the timber, while the miter end of the tool is turned in the direction of the operator. In this operation the pitch of a hip-cut is determined at 27, and for this purpose the end of the tool opposite the operator is moved outwardly, as indicated in dotted lines, and the scale at 15, operating in connection with the edge of the timber at 28, serves to give the exact degree of the pitch of a hip-cut, the said cut being indicated by the various lines at 29.

From the foregoing description it will be seen that my improved tool comprises an elongated base or head having a front straight edge and provided with two arms which project from the front straight edge and are separated by an angle of ninety degrees, the in-

ner edges of said arms ranging outwardly from a point adjacent to the middle portion of the front straight edge of the base or head, ⁷⁰ and said arms may be formed separately, if desired, instead of integrally, and the back of the base or head may be straight or of other form.

In Figs. 4, 5, and 6 I have only illustrated ⁷⁵ four of the methods of using my improved tool in order to accomplish certain results; but various other results may be obtained, as will be readily understood by any one skilled in the art, and my improved tool may ⁸⁰ be used for making octagonal cuts, miter-cuts, and for many other purposes, the adjacent edges of the arms ^{8a} and ^{9a} serving particularly for the purpose of making octagonal cuts. ⁸⁵

Having fully described my invention, what I claim as new, and desire to secure by Letters Patent, is—

1. A carpenter's tool or square comprising a base-piece having a front straight edge and composed of top and bottom parts, one of which is wider at the straight edge than the other, one end of said base-piece being also formed at a right angle to the straight edge thereof, and the other end at an angle of ⁹⁰ forty-five degrees to the said straight edge, and a plate set into the front straight edge of the base-piece longitudinally and centrally ⁹⁵ thereof and provided with two arms, which taper outwardly, the outer edge of one of ¹⁰⁰ said arms forming a right angle to the straight edge of the base-piece and the outer edge of the other arm forming an angle of forty-five degrees to the said straight edge of the base-piece, said plate being also cut out ¹⁰⁵ opposite the central portion of the base-piece so as to form said arms and an angle of ninety degrees at the intersection of the adjacent edges of said arms adjacent to the middle of ¹¹⁰ the base-piece, substantially as shown and described.

2. A carpenter's tool or square comprising a base-piece having a front straight edge and composed of top and bottom parts, one of which is wider at the straight edge than the ¹¹⁵ other, one end of said base-piece being also formed at a right angle to the straight edge thereof, and the other end at an angle of forty-five degrees to the straight edge, and a plate set into the front straight edge of the base-piece longitudinally and centrally ¹²⁰ thereof and provided with two arms, which taper outwardly, the outer edge of one of said arms forming a right angle to the straight edge of the base-piece and the outer edge of the other ¹²⁵ arm forming an angle of forty-five degrees to the said straight edge of the base-piece, said plate being also cut out opposite the central portion of the base-piece so as to form said arms and an angle of ninety degrees at the ¹³⁰ intersection of the adjacent edges of said arms adjacent to the middle of the base-piece, the arm, the outer edge of which forms an angle of ninety degrees to the straight edge of the

base-piece being also provided with a plurality of rows of scale-holes and said arm being also provided centrally of the base thereof with a hole in line with the inner inclined 5 edge of the other arm, substantially as shown and described.

3. A carpenter's tool or square comprising a base-piece having a front straight edge and composed of top and bottom parts, one of which 10 is wider at the straight edge than the other, one end of said base-piece being also formed at a right angle to the straight edge thereof, and the other end at an angle of forty-five degrees to the straight edge, and a plate set into 15 the front straight edge of the base-piece longitudinally and centrally thereof and provided with two arms which taper outwardly, the outer edge of one of said arms forming a right angle to the straight edge of the base- 20 piece and the outer edge of the other arm forming an angle of forty-five degrees to the said straight edge of the base-piece, said plate being also cut out opposite the central portion of the base-piece so as to form said arms 25 and an angle of ninety degrees at the intersection of the adjacent edge of said arms adjacent to the middle of the base-piece, the arm, the outer edge of which forms an angle of ninety degrees to the straight edge of the 30 base-piece being also provided with a plurality of rows of scale-holes and said arm being also provided centrally of the base thereof with a hole in line with the inner inclined 35 edge of the other arm, and said first-named arm, being also provided on the opposite sides of its outer or straight edge with inclined scale-marks, and the last-named arm being provided on its inner or inclined edge with scale-marks, substantially as shown and de- 40 scribed.

4. A carpenter's tool or square, comprising a base-piece having a front straight edge and composed of top and bottom parts, one of which is wider at the straight edge than at 45 the other, one end of said base-piece being also formed at a right angle to the straight edge thereof and the other end at an angle of forty-five degrees to said straight edge and two tapered arms projecting from said straight 50 edge, said arms being separated by an angle of ninety degrees at their adjacent edges and

said adjacent edges converging and intersecting adjacent to the middle of the base-piece, the outer edge of one of said arms being at an angle of forty-five degrees to the straight 55 edge of the base-piece, and in line with the corresponding end of the base which is similarly formed, the outer edge of the other arm being at an angle of ninety degrees to the straight edge of the base-piece, and in line 60 with said end of the base-piece which is similarly formed, substantially as shown and described.

5. A carpenter's tool or square, comprising a base having a front straight edge and composed of top and bottom parts, one of which is wider at the straight edge than at the other, one end of said base-piece being also formed at a right angle to the straight edge thereof and the other end at an angle of forty-five 70 degrees to said straight edge and two tapered arms projecting from said straight edge, said arms being separated by an angle of ninety degrees at their adjacent edges and said adjacent edges converging and intersecting adjacent to the middle of the base-piece, the outer edge of one of said arms being at an angle of forty-five degrees to the straight edge of the base-piece, and in line with the corresponding end of the base-piece which is similarly formed, the outer edge of the other arm being at an angle of ninety degrees to the straight edge of the base-piece, and in line 80 with said end of the base-piece which is similarly formed, the outer edge of the last-named 85 arm being also provided at both sides with inclined or diagonal scale-marks, substantially as shown and described.

6. A carpenter's tool comprising a base having a straight edge and an arm projecting 90 therefrom, and provided with a plurality of scale-holes arranged longitudinally thereof, said base being wider at one side than at the other, substantially as shown and described.

In testimony that I claim the foregoing as 95 my invention I have signed my name, in presence of the subscribing witnesses, this 3d day of September, 1901.

JOSEPH UBERT DUBY.
